UNITED STATES PATENT OFFICE.

JOHN W. SIBBALD, OF NEW YORK, N. Y.

GOLF TEE.

Application filed October 10, 1925. Serial No. 61,629.

To all whom it may concern:

Be it known that I, JOHN W. SIBBALD, a citizen of the United States, residing at New York, in the county of New York and 5 State of New York, have invented certain new and useful Improvements in Golf Tees, of which the following is a specification.

The invention relates to an improved golf ball tee adapted to be carried about conveniently by a player, said tee being provided with adjustable means for supporting the ball at a height to suit the requirements, for example, a tee of the character set forth in my prior U. S. Letters Patent No. 1,413,496. 15 The present invention relates more particularly to a construction of tee of this type whereby possible damage to the adjustable portion thereof is prevented and, furthermore, whereby a guide may be provided to 20 assist a player in the striking of the ball. In the tee set forth in my aforesaid patent, the ball support member is adjustably mounted in a boss or hub; but I have found that if the same be frequently struck by a 25 golf club there is danger of such hub becoming damaged to the extent even of interfering with the adjustment of the ball supporting member, particularly if the tee be made of comparatively light material as 30 aluminum and which is a highly desirable material to employ for this purpose. The present invention obviates any possibility of damage in this respect to the ball supporting member; and the novel structure is 35 shown more particularly in the accompanying drawings, wherein—

Fig. 1 is a plan view of the improved tee, and Fig. 2 is a side elevation thereof.

Referring to the drawings, 10 designates 40 a generally segmental base member having a radially disposed approach incline 11 merging into the circumference of said base, the portions either side being cut away, leaving upstanding from the base the radially disposed incline or arm 11. At the inner end is a central and hub portion 12 for retaining the adjustable ball support 13 which hub, as in my prior construction, is of substantial proportions; and the arm 11 is designed 45 to merge therein, being radially directed thereto with its inclined upper surface 14 extending from the circumference of the base 10 upwardly substantially to the upper edge of said hub, as indicated more 50 clearly in Fig. 2 of the drawings. The sides of incline 11, however, extend abruptly

from the surface of the base and the arm is effectively set off therefrom. Moreover, the surface of the base at both sides of the incline 11 at the immediate circumference 60 portion is beveled off, as at 15, toward the circumference to assist also in deflecting a blow upwardly should the stroke be slightly from one side or the other. This improved incline member provides a substantial approach surface in driving as well as a reinforcement of the hub so that all damage thereto is obviated in the striking of the same by a club and there is no tendency of the ball supporting member 13 binding 65 therein and thus cause the tee to lose the advantage of adjustment. Moreover, in case a club should strike the tee, the blow will be deflected upwardly due to the inclined approach surface 11 or the beveled portions 15 70 and, furthermore, will be guided toward the ball. A still further advantage of the improved construction resides in the fact that in instances where the tee is hit rather than the ball, the former is not hurled to any 75 great distance due to a downward component of the blow resulting from impact upon the said inclined approach surfaces. The ample surface of the base portion provides, moreover, for adequate support of the tee 80 as a whole and renders the same sufficiently stable in use.

I claim:—

1. A golf ball tee, comprising a supporting base having a protruding boss or hub, 90 an arm with inclined approach and guide surface extending from said base substantially to the top of the said hub, and a recessed member adjustably mounted in said boss adapted to receive a golf ball. 95

2. A golf ball tee, comprising a segmental base support having a centrally located protruding boss or hub, a radial arm with inclined approach and guide surface extending substantially to the top of said hub from 100 the circumference of said base, and a recessed member adjustably mounted in said boss adapted to receive a golf ball.

3. A golf ball tee, comprising a segmental base support having a centrally located protruding boss or hub, a radial arm with abrupt sides and inclined approach and guide surface extending substantially to the top of said hub from the circumference of 105 said base, and a recessed member adjustably mounted in said boss adapted to receive 110 a golf ball.

4. A golf ball tee, comprising a segmental base support having a centrally located protruding boss or hub, a radial arm with abrupt sides and inclined approach and guide surface extending substantially to the top of said hub from the circumference of said base, the immediate circumference por-

tion thereof at both sides of the radial arm being beveled to the circumference of the base, and a recessed member adjustably 10 mounted in said boss adapted to receive a golf ball.

In testimony whereof I affix my signature.
JOHN W. SIBBALD.
